UNITED STATES PATENT OFFICE.

PIETER NOTENBOOM, OF ROTTERDAM, NETHERLANDS.

FRUIT-SORTING MACHINE.

1,310,921.

Specification of Letters Patent. Patented July 22, 1919.

Application filed August 26, 1916. Serial No. 117,041.

To all whom it may concern:

Be it known that I, PIETER NOTENBOOM, residing at No. 130, B Agniesestraat, Rotterdam, the Netherlands, have invented certain new and useful Improvements in Fruit-Sorting Machines, of which the following is a specification.

This invention relates to a fruit sorting machine of the kind in which fruit, especially tomatoes and generally all other bulbous fruit and vegetables, such as plums, oranges, apples, potatoes, bulbs, etc., are sorted according to their size.

In the machines of the types known the fruits were more or less liable to be bruised or damaged on their way through the machine. This disadvantage was particularly met with in case of soft, sappy fruits such as tomatoes, so that the senders very often suffered considerable loss through a great percentage of the fruit having to be refused on arrival, owing to bruises received during the sorting in the machine.

This drawback is avoided in the sorting machine according to this invention, in which the fruits are sorted according to their sizes without any danger of getting bruised or damaged and with a speed excelling that attained up to the present with any other similar machine.

The construction or form of a machine embodying the invention is shown by way of example in the accompanying drawings.

Figure 1 shows a top-view of the machine, with the arrangement, along which the fruits to be sorted are supplied to the machine, being cut away across the line C—C of Fig. 2.

Fig. 2 is a vertical longitudinal section taken on the line A—A in Fig. 1, showing the charging gutter in position.

Fig. 3 is a vertical cross-section taken on the line B—B in Fig. 2.

The charging gutter 1 is arranged in an inclined position on top of the sorting machine. The fruits to be sorted are supplied to the gutter, roll through the opening at the lower end 2 upon the incline 3 and from this upon the sorting bed 4, which latter too is placed slightly slanting. The sorting bed is provided with a number of holes 6, increasing in diameter from the incline 3 to the end 5 of the bed. The section of these holes varies in accordance with the kind of fruit to be sorted and with the various sizes re-

quired. For instance, if the machine shall be used for sorting tomatoes, the holes in the sorting bed may suitably receive the following successive sizes: $1\frac{3}{8}''$, $1\frac{1}{4}''$, $2''$, $2\frac{1}{4}''$ and $2\frac{1}{2}''$.

The holes may according to their sizes be divided into sections, for example three rows of holes of the first size, four rows of holes of each of the three next bigger sizes and three rows of holes of the last mentioned size.

The tomatoes, being moved across the sorting bed, in the direction from the incline 3 to the end 5, will successively fall through the holes which correspond with their sizes.

For other kinds of fruit than tomatoes holes of different sizes and arranged in sections each with a suitable number of rows may naturally be provided. Preferably the sorting bed is made interchangeable, so that one and the same machine may be made fit for sorting all different kinds of fruits by simply replacing the sorting bed.

In order to keep the different sizes of the sorted fruits separated from each other partitions 7 are provided underneath the sorting bed, forming divisions, which can be closed at the front side by means of slides 9. On these slides being withdrawn the sorted fruits roll into the baskets 10, placed underneath the divisions 8. Underneath the sorting bed 4 further a canvas sheet 11 is stretched in an inclined position on which the fruits are caught after being sorted and along which they roll into their respective divisions 8 and 12.

Fruits of larger size than the biggest hole 6 in the sorting bed 4 are discharged at the end 5 of same into the receptacle 12, from which they are removed at suitable intervals.

Thus tomatoes of abnormal sizes which are faulty are removed.

In order to secure a quick and constant working of the machine the sorting bed 4 is provided with an arrangement, by which the fruits are caused to move constantly in the longitudinal direction of the bed from the incline 3 to the end 5. This arrangement consists of a number of laths 21, which are moved through slots connecting the holes in the longitudinally situated rows of the sorting bed.

The movement is such, that the fruits which have settled in holes too small for the

fruits to fall through, are lifted and moved on in the longitudinal direction of the bed to the next bigger holes. This operation is regularly repeated so that the fruits owing 5 to the gradient of the sorting bed move from one hole into the next until they meet holes of sufficient sizes to fall through on the canvas sheet from which sheet they roll into their respective receptacles.

10 The laths 21 receive their movement from a crank 13 with which they are at one end rotatably connected, while the other end is loosely fixed to the spindle 14.

15 The crank 13 is operated by means of a handle 15 and is at the end provided with a lever 16 of the same length as the crank 13. This lever 16 is placed at an angle of 90° in relation to the crank 13.

20 The lever 16 is revolubly connected to a rod or bar 17 which again is suspended from the form 18, fixed to the end of the shaft 19. The shaft 19 again is by means of connecting rods 20 and oscillating suspension rods 22 connected to the spindle 14 of the laths.

25 By causing the crank 13 to revolve around its axis the laths 21 will partly oscillate and partly move up and downwardly, whereby they successively will be moved upwardly into the longitudinally arranged 30 slots in the bed, perform their longitudinal movement through these slots and finally will disappear beneath the surface of the sorting bed.

35 The connecting rods 20, which cause the spindle 14 to perform its up and down motion, being longer than the fork 18, the distance over which the laths at the spindle end 14 will be moved and the speed of this movement will be greater than at the crank-end 40 13. This arrangement will result to the laths being lifted higher through the slots at the end of the sorting plane than at the beginning. This is of importance as the bigger sizes of the fruits will sink deeper 45 into the large sized holes at the end of the bed, than the small fruits into the small holes at the beginning of the same.

50 The quantity of tomatoes sorted with the machine according to this invention and described above amounts to over two pounds at each revolution of the handle 15.

Assuming the speed at which the handle 55 15 is operated to be one revolution per second which may be easily attained the machine will be able to sort about 8,000 pounds

of fruit per hour without bruising or damaging same.

Having thus described my invention, what I claim as new and desire to secure by Letters Patent is:—

60 1. In a fruit sorting machine, in which the fruit is passed over a fixed inclined bed formed with a number of sorting holes increasing in diameter from the upper charging end to the lower discharging end, the combination of a plurality of laths adapted to be moved through a series of slots connecting the sorting holes, and means for imparting simultaneously a longitudinal movement to said laths and a differential vertical movement to the extremities thereof, whereby said laths engage any fruit, which may have settled in sorting holes of too small diameter, at their lowest point, thus lifting said fruit and causing the same to move along the bed until it reaches the sorting holes of proper diameter.

65 2. In a machine of the class described, the combination with a fixed inclined bed formed with a number of sorting holes of a plurality of laths adapted to be moved through a series of slots connecting the holes, and means for imparting to said laths a combined reciprocating and vertical movement of such character that said laths travel 70 through a greater vertical distance at the discharging end than at the charging end of the sorting bed.

75 3. In a machine of the class described, the combination with a fixed inclined bed formed with a number of sorting holes, of a plurality of laths adapted to be moved through a series of slots connecting the holes, a rotating crank to which said laths are rotatably connected at one end, and oscillating means from which the opposite ends of said laths are suspended, the connection between said laths and the oscillating means being such that upon the rotation of the said crank, the laths are caused to 80 travel through a vertical distance which is greater at the discharging end of the sorting bed than at the charging end thereof.

85 In testimony whereof I affix my signature in presence of two witnesses.

PIETER NOTENBOOM.
